WINDOW LATCH

Sheldon Ruderfer, Woodbridge, Va., assignor to North American Die Casting Corporation, Fredericksburg, Va.

Filed Mar. 4, 1974, Ser. No. 447,590

Term of patent 14 years

Int. Cl. D8—07, 09

U.S. Cl. D8—111

FIG. 1

FIG. 2

FIG. 3

FIG. 4

FIG. 1 is an enlarged perspective view illustrating the window latch of this invention in its latch closed position;

FIG. 2 is a left end view of the latch of FIG. 1;

FIG. 3 is a front elevational view of the latch of FIG. 1 in its latch open position; and

FIG. 4 is a rear elevational view of the latch of FIG. 1.

I claim:

The ornamental design for a window latch, as shown and described.
